HARVEY J. LOUNSBURY, OF GLEN ELLYN, ILLINOIS, ASSIGNOR TO W. H. MINER, INC., OF CHICAGO, ILLINOIS, A CORPORATION OF DELAWARE

RAILWAY DRAFT RIGGING

Original application filed November 5, 1928, Serial No. 317,148, and in Canada September 13, 1929. Divided and this application filed January 14, 1931. Serial No. 503,679.

This invention relates to improvements in railway draft riggings.

This application is a division of applicant's co-pending application, Serial No. 317,148 for railway draft riggings filed November 5, 1928.

The main object of the invention is to provide a draft rigging including a coupler, a yoke connected thereto, and cooperating shock absorbing means within the yoke, and a casting secured to the draft sills through which the coupler shank and the yoke extend, the casting acting as a front stop member, wherein the yoke is so designed as to support the coupler shank in proper alignment with the shock absorbing means and the sides of the yoke at the point of connection with the coupler shank are reinforced to strengthen the same and especially the key receiving opening thereof, and the side walls of the stop casting which receive the coupler key are formed so as to accommodate the reinforced sections of the yoke upon lateral swinging movement of the same.

In the drawing forming a part of this specification, Figure 1 is a longitudinal, vertical, sectional view through a portion of the underframe structure of the car illustrating my improvements in connection therewith. Figure 2 is a horizontal, longitudinal, sectional view, broken away, corresponding substantially to the line 2-2 of Figure 1. Figure 3 is a transverse, vertical, sectional view corresponding substantially to the line 3-3 of Figure 1. And Figure 4 is a detailed, perspective view of a portion of the combined striking casting and front stop member employed in my improvements.

In said drawing, 10-10 indicate channel shaped center or draft sills of a railway car underframe structure. The end sill structure of the car comprises members 13-13 and 14, which are suitably connected to the draft sills. The coupler of the car is designated by 15, the shank and a portion of the head thereof being shown.

In carrying out my invention, I provide a combined striking casting and front stop member A, and a vertical yoke member B enclosing a shock absorbing mechanism, gen-

erally indicated by C, and a cooperating front main follower D. A pressure-transmitting member E is employed in connection with the shock absorbing mechanism and extends through the main follower and is interposed between the inner end of the coupler shank and the shock absorbing mechanism.

The shock absorbing mechanism shown is of the friction type, including a friction casing 41, a wedge member 44 and the usual friction shoes having sliding frictional contact with the interior of the casing 41. The shoes are resisted in their movement by the usual spring contained within the casing 41 and the parts are held assembled by a retainer bolt 52 extending through the wedge and having the outer end thereof anchored to the pressure-transmitting member E. The pressure-transmitting member E is provided with lateral flanges 49-49 at the outer end thereof, which limit the inward movement of the same. Further detailed description of the friction shock absorbing mechanism, pressure-transmitting member and front follower is not required in this application, as this subject matter is described fully and in detail in my copending application, Serial No. 317,148, hereinbefore referred to.

The combined striking casting and front stop member A is in the form of a box-like member open at the bottom side and front and rear ends and having a horizontal top wall 16 and vertically disposed spaced side walls 18-18. The top wall is downwardly offset at the forward end, as indicated at 19, and is provided with a rearwardly extending elongated central opening 20 which accommodates the upper section of the yoke B. At the forward end, the side walls of the casting A are provided with relatively thick lateral flanges 21-21 which are formed integral with a transverse wall section 22 at the upper side of the casting forming a continuation of the top wall thereof. The side flanges 21, together with the wall section 22, form the striking plate member proper of the casting A. The transverse wall 22 is also provided with a rearwardly extending horizontal top wall section 23 which engages over the angle end sill member 14. The side walls 18 of the

casting A are preferably secured to the webs of the side sills 10 by rivets, as most clearly shown in Figures 1, 2 and 3. The side walls 18 of the casting are provided with longitudinal openings 24—24 adapted to accommodate the usual coupler key. As most clearly illustrated in Figures 3 and 4, the key receiving openings 24 are reinforced by spaced, horizontally disposed, top and bottom wall sections 25—25 and end wall sections 26—26. The wall sections 25 are connected to the main body portion of the corresponding side wall 18 by outwardly offset portions 56—56 which provide walls which converge laterally outwardly of the casting. The outer wall sections 25 define the key guide slot proper and, as shown in Figures 3 and 4, are spaced apart the proper distance vertically to accommodate and guide the key. The offset wall sections 56 provide concave seats or recesses which accommodate certain reinforcements of the yoke, as herein-after more clearly pointed out.

The inner ends of the walls 18 are thickened, as indicated at 27—27, to provide the front stop lugs proper of the railway draft rigging. The laterally enlarged sections 27 are suitably reinforced by horizontally disposed top and bottom ribs 28 formed integral 30 with the inner faces of the side walls. Additional reinforcing ribs 29—29 are also provided at the top and bottom sides of the key receiving openings. As clearly shown in Figures 1 and 2, the webs of the center sills 10 are cut away so as to accommodate the offset wall sections 56 of the side walls 18 of the casting A and permit assembly of the casting between the draft sills by inserting the same longitudinally between the sills 40 from the end of the car.

The yoke B comprises top and bottom arm members 30—30 and a vertical rear end section, not shown, formed integral with the top and bottom arms. At the front end of the yoke, the top and bottom arms are connected by vertical side walls 31—31, thereby forming a box-like end structure adapted to accommodate the coupler shank. As most clearly shown in Figure 1, the top arm 30 of the yoke is downwardly offset at the forward end, as indicated at 32, and has a vertical flange section 33 at the outer end thereof, which is adapted to abut the inner end of the coupler head. The bottom arm 30 of the yoke has an upwardly offset section 34 at the extreme forward end thereof, which directly supports the bottom side of the coupler shank adjacent the head of the coupler. The section 34 is preferably provided with a downwardly extending flange portion 35 at the extreme forward end thereof, which is in substantial vertical alignment with the flange 33 of the top arm. At the inner ends, the side walls 31 are substantially parallel, 55 as shown in Figure 2, while the front end

sections thereof diverge outwardly to correspond with the formation of the front end portion of the coupler shank.

The extremities of the side walls 31 at the front end of the casting are provided with vertically disposed lateral flanges 36—36 which lie in the same plane as the flanges 33 and 35. The side wall members 31 are provided with aligned coupler key receiving openings 37—37, which are reinforced at the forward ends by enlargements 38—38 and top and bottom rib members 39—39, which are cut away at their inner ends, as shown. As will be evident upon reference to Figure 3, the enlarged portions 38 which reinforce the key receiving openings 37 of the yoke will be accommodated within the offset or recessed portions of the side walls of the stop casting A when the yoke is swung laterally to either side of its centered position to accommodate itself to the lateral swinging movement of the coupler when the cars are being operated on curved track. By this arrangement, the coupler key receiving openings of the yoke are properly reinforced without in any way interfering with the lateral swinging movement of the coupler and yoke member. The coupler shank is connected to the yoke B by the usual transverse key 40 which extends through aligned openings in the coupler shank, the openings 37 of the yoke, and has the outer ends thereof working in the guide slots 24 of the casting A. The key 40 is of the usual headed type and has any well known form of retaining means at the free end 100 thereof.

In the operation of my improved railway draft rigging, assuming that the coupler is being pulled forwardly or outwardly in draft, the yoke B will be carried forwardly therewith through the medium of the connecting key 40, thereby pulling the casing of the friction shock absorbing mechanism C forwardly while the wedge block 44 is held stationary by engagement with the main follower D, which is held against outward movement by the stop members 27 of the casting A. Movement of the parts is limited by engagement of the front end of the casing of the shock absorbing mechanism with the main follower D.

Upon a buffing action being applied to the coupler, the same will be carried inwardly, thereby forcing the pressure transmitting member E inwardly also and carrying the wedge block 44 therewith, the casing of the friction shock absorbing mechanism being held stationary at this time by the rear stop members. Inasmuch as the pressure transmitting member E is longitudinally movable with respect to the follower D, there will be a relative movement of the pressure transmitting element with respect to the follower D, equal to the clearance between the flanges 49 on the pressure transmitting member and 125

the abutment face at the front side of the follower. In addition, there will be a movement of the pressure transmitting member equal to the clearance between the main follower and the front end of the casing of the friction shock absorbing mechanism. In other words, during the buffing action of the mechanism, the maximum movement of the friction wedge system with respect to the 5 casing is equal to the clearance between the main follower and the front end of the friction casing, plus the clearance between the flanges of the pressure transmitting element and the main follower.

10 It will be evident that the movement of the parts during a buffing stroke will be greater than the movement of the parts during draft by an extent equal to the clearance between the flanges on the pressure transmitting element and the main follower D.

15 From the preceding description, taken in connection with the drawing, it will be evident that I have provided a yoke construction having the key receiving openings thereof 20 amply reinforced, without restricting the lateral swinging movement of the yoke, by providing recessed portions in the side members of the stop casting without in any way weakening the structure of the side walls at the key receiving openings thereof.

25 While I have herein shown and described what I consider the preferred manner of carrying out my invention, the same is merely 30 illustrative and I contemplate all changes and modifications which come within the scope of the claims appended hereto.

35 I claim:

1. In a railway draft rigging, the combination with spaced draft sills; of a coupler; 40 a yoke anchored to the coupler by means of a key, the side walls of the yoke being slotted to receive the coupler key, said slots being reinforced by wall portions projecting laterally outwardly from the sides of the yoke; and a 45 front stop casting secured to the sills, the side walls of said casting being slotted to provide coupler key receiving openings, the walls of said openings being connected to the casting proper by outwardly projecting wall sections 50 forming seats adapted to embrace and accommodate the reinforcing wall portions of the yoke when the latter is swung laterally.

55 2. A combined front stop and striking casting for railway cars having spaced side walls provided with coupler key receiving slot sections, said slot sections being defined by outwardly projecting wall portions, said wall 60 portions converging outwardly and having their outermost sections cooperating with the coupler key to guide the same.

65 3. A front stop member for railway draft riggings comprising a plate-like section adapted to be secured to the web of one of the draft sills of a car, said plate-like section being provided with a longitudinal opening de-

fined by outwardly offset top, bottom and end wall sections, the top and bottom wall sections converging outwardly and forming, at their outer extremities, top and bottom guide walls, adapted to cooperate with a coupler 70 key.

In witness that I claim the foregoing, I have hereunto subscribed my name this 12th day of January, 1931.
